Primary Examiner — Elizabeth J Oswecki

(57) **CLAIM**

The ornamental design for a shoe, as shown and described.

DESCRIPTION

FIG. 1 is a top, front, left side perspective view of a shoe showing my new design;

FIG. 2 is a left side view of the shoe;

FIG. 3 is a right side view of the shoe;

FIG. 4 is a top view of the shoe;

FIG. 5 is a bottom view of the shoe;

FIG. 6 is a front view of the shoe; and,

FIG. 7 is a rear view of the shoe.

The broken lines are illustrative of stitching forming no part of the claimed design.

1 Claim, 3 Drawing Sheets
